UNITED STATES PATENT OFFICE.

SVEN A. JOHNSON, OF BROOKLYN, NEW YORK.

AIR-COMPRESSOR.

1,350,159.

Specification of Letters Patent. Patented Aug. 17, 1920.

Application filed August 1, 1919. Serial No. 314,713.

To all whom it may concern:

Be it known that I, SVEN A. JOHNSON, a citizen of the United States, residing at Brooklyn, in the county of Kings and State 5 of New York, have invented certain new and useful Improvements in Air-Compressors, of which the following is a specification.

This invention has relation to air compressors and has for an object to provide a 10 compressor of the rotary type designed to eliminate friction to the greatest possible extent, to simplify the construction, and to provide for a plurality of compression impulses during each revolution of the rotor, 15 in a manner to be hereinafter described.

Another object of the invention is to provide an air compressor having the characteristics above set forth which includes a casing, and a rotor adapted to travel therein in an 20 extensive path, with abutment pivotally arranged around the casing and adapted to operate in members secured in the rotor whereby to secure a plurality of compressions between adjacent abutment during each revolution of the rotor.

Another object of the invention is to provide a device of the character above set forth which may be utilized not only as an air compressor, but also as a vacuum pump according to the point of connection of the intake and delivery and also as a prime mover when air or steam is admitted thereto under pressure.

In addition to the foregoing, this invention comprehends improvements in the details of construction and arrangement of parts, to be hereinafter described and particularly set forth in the appended claims.

In the accompanying drawings in which 40 similar and corresponding parts are designated by the same characters of reference throughout the several views in which they appear,

Figure 1 is a view in section taken on the line 1—1 of Fig. 2, and

Fig. 2 is a central section taken transversely and vertically through the foregoing figure.

The casing of my improved air compressor 50 is of a compound structure, and includes end plates 10 and 11 mounted upon base plates 12 and arranged in spaced relation, the plate abutting to dispose the plates 10 and 11 in proper relation. A pair of annular members or casings 13 and 14 are disposed between the plates 10 and 11 and located be-

tween said casings is a division plate 15. The plates 10 and 11 are formed with central apertures to receive a shaft 16 which passes centrally through the casings 13 and 14 and 60 through a central opening in the plate 15 as shown. Each casing 13 and 14 is formed with a channel 17 which extends very nearly throughout the entire circumference of the casing and communicates with a port 18 at 65 the upper end of the casing. Each casing 13 and 14 is furthermore formed with a plurality of transversely extending passages or cavities 19 which register with similar cavities 20 in the end plates 10 and 11 and also 70 with cavities 21 in the partition. Said cavities 19, 20, and 21 serve to permit the circulation of water therethrough whereby to cool the casing during operation of the machine. The inner surface of each plate 10 75 and 11 is furthermore formed with an annular channel 22, and said channels communicate with transverse openings, suitably capped to receive couplings 23. Mounted on the shaft within each casing is an eccentric 80 24, the eccentrics being arranged relatively in opposed relation as shown in Fig. 2, and mounted on each eccentric is a rotor indicated at 25. Each rotor is cylindrical in form, somewhat smaller than the internal 85 diameter of the casing in which it is located, and of an open work construction to reduce weight as much as possible. Each rotor is furthermore formed at 4 or more points with relatively large transverse openings or recesses 26, suitably machined to receive oscillating cylindrical members 27, each member being formed with a transverse diametrically extending recess 28 extending very nearly 90 through the entire diameter of the member. 95 As stated, the rotor is of an open work construction to provide recesses or cavities 29 therein, and said cavities communicate with the interior of the recess 26 through the medium of passages 30. Each oscillating member 27 is furthermore provided with a pair 100 of passages 31 which communicate the interior of the recess 28 with the exterior of the member as shown. A plurality of abutments are provided, in the present instance four being 105 shown, each abutment consisting of a plate 32 adapted to snugly fit the recess 28 of one of the members 27 and an enlarged cylindrical portion 33 at one edge to snugly fit within a cavity 34 formed in the wall of 110 the casing. Each plate 32 is furthermore formed with a longitudinal extending pas-

sage 35 which extends from one edge of the plate to the opposite edge bearing the cylindrical portion 33 and effect an exit as at 36 at one side of the plate, a valve 37 being located at that point to open inward. It will thus be seen that owing to the provision of the abutment a plurality of chambers are provided between the abutment defined by said abutment, the casing wall and the rotor, 10 the chambers varying in capacity according to the position of the rotor within the casing. A plurality of passages 38 are provided communicating between each of the chambers above mentioned and the annular passage 17 of each casing, and each passage 38 is provided with a valve 39 designed to open outward. If desired the outer wall of the casing may be apertured at points opposite the passages 38 and normally closed by means of plates 40 whereby said plates may be removed to gain access to the valve 39.

During operation of the machine if it is desired to employ the same as a compressor the shaft is rotated in the direction of the arrow shown in Fig. 1 in which event the intake will be through the couplings 23. During rotation of the rotor the chambers between the abutment will be consecutively enlarged in capacity and during the period 25 of enlargement the intake will be through the coupling 23 as mentioned, the annular channel 22 into the recess 29, passages 30 and 31, passage 35 and into the chamber through the valve opening 36. As each chamber 30 reaches its maximum capacity and becomes subsequently reduced the air contained therein is discharged through the valve 39 and into the channel 17 from which to effect 35 an exit through the port 18 to a reservoir or any place designed to receive the air.

From the foregoing it will be seen that there is very little friction because of the free movement of the sliding surfaces of the abutment and the rotor and hence this machine may be operated with maximum efficiency. Conversely, by introducing air or steam under pressure into the couplings 23 the device may be operated as a prime mover to drive machinery. Other uses and advantages will readily occur to those skilled in the art to which this invention appertains.

While I have illustrated and described my invention with some degree of particularity, I realize that in practice various alterations therein may be made. I therefore 55 reserve the right and privilege of changing the form of the details of construction or otherwise altering the arrangement of the

correlated parts without departing from the spirit of the invention or the scope of 60 the appended claims.

Having thus described my invention, what I claim as new and desire to secure by United States Letters Patent is:

1. An air compressor including a casing, 65 and having inlet and outlet, a rotor mounted therein, a plurality of abutments having passages therethrough oscillatably mounted in the casing and adapted to slidably engage the rotor, and valves in said abutments. 70

2. An air compressor including a casing having inlet and outlet, valves controlling the outlets of the casing, a rotor mounted within the casing, a plurality of abutments having passages therethrough mounted in 75 the casing to slidably engage the rotor, and valves for controlling the inlet are mounted in said abutment.

3. An air compressor including a casing having inlet and outlet, a rotor mounted 80 for movement in the casing in an eccentric path, a plurality of members rotatably mounted in said rotor, and a plurality of abutments having passages therethrough slidably engaging said rotatable member 85 and oscillatably mounted in the casing.

4. An air compressor including a casing having inlets and outlets, a rotor mounted in the casing for movement in an eccentric path, a plurality of cylindrical members 90 transversely slotted and rotatably mounted in said rotor, a plurality of abutments having passages therethrough slidably engaging the slot of the rotatable members and oscillatably mounted in the casing, and valves 95 in said abutment for controlling the inlet.

5. An air compressor including a casing having inlets and outlets, a shaft mounted therein, an eccentric mounted on the shaft, a rotor mounted on said eccentric to travel 100 within the casing in an eccentric path, a plurality of members rotatably mounted in said rotor and having transverse slots, a plurality of abutments having passages extending therethrough, oscillatably mounted 105 in the casing and slidably engaging the slots of the members, valves controlling the outlet of the casing, and valves in said abutments controlling the passages therethrough. 110

In testimony whereof I affix my signature in presence of two witnesses.

SVEN A. JOHNSON. [L.S.]
